UNITED STATES PATENT OFFICE

JOHN C. LINDNER, OF ROCHESTER, NEW YORK, ASSIGNOR TO GENERAL RAILWAY SIGNAL COMPANY, OF ROCHESTER, NEW YORK

PROTECTIVE DEVICE FOR INTERLOCKING SYSTEMS

Application filed August 15, 1930. Serial No. 475,464.

This invention relates to protective devices for interlocking systems, and more particularly to means whereby interlocking systems are protected against improper operation of the traffic controlling devices, due to crosses between operating wires and other derangements of wiring and connections.

In interlocking systems, the distant traffic controlling devices are usually operated electrically over control wires from the tower. To obviate the improper operation of such traffic controlling devices as, signals, switches, derails, and the like, due to crosses, shorts and grounds in the system, which would also cause current to flow in a direction opposite to the normal current flow, a relay is interposed, which is responsive only to reverse current and is effective to interrupt the main source of current. With the source of energy cut off from the device which the relay protects, the device cannot again be operated until the relay is restored to its normal position, and it is desirable in restoring the relay to avoid forcibly holding the control circuit closed in the event that an abnormal condition still exists in the circuit.

One of the objects of the present invention is to provide a means for protecting a controlled device as described above, which will be simple as well as reliable in its operation, with a convenient and safe means of restoring the circuit after the operation of the protective device.

Other objects, purposes, and characteristic features of the invention will appear as the description of the invention progresses.

In describing the invention in detail, reference will be made to the accompanying drawings, which are merely illustrative of the invention and are not intended in any manner in a limiting sense, and in which:—

Fig. 1 illustrates a typical switch controlling circuit, forming a part of an interlocking system, and embodying the present invention.

Fig. 2 is a side elevation of a protective device embodying the present invention; and

Fig. 3 is an end view of the device illus-

trating the armature and contact arrangement.

In the controlling system, illustrated in Fig. 1, a switch machine SM, consisting of the motor armature M and field winding F, with its accompanying pole changer, is shown connected to operate a track switch TS. This switch machine is electrically operated and may be of any suitable construction such as shown in the patent to Howe No. 1,466,903 dated Sept. 4, 1923.

The control of the switch machine SM is obtained by a control lever L of an interlocking system, which lever is mechanically interlocked with conflicting levers by a tap-pet bar 25 operated by a roller 26 moving in slot 27. The contact arrangement of the lever and the indication-latch mechanism operated by the indication coils IM and safety coils S are shown, but will not be described in detail, as they are of the type specifically described in the patent to Howe No. 1,163,154 dated Dec. 7, 1915.

The protective device P¹ is shown protecting the switch machine SM as controlled by lever L, and a second protective device P² is shown to indicate the invention as applied to another similar switch machine and its corresponding control lever, the latter being indicated merely by a dotted rectangle.

A cross indicator is conveniently shown as being a lamp I, and a restoring switch for all of the protective devices P¹, P², etc. in the system is represented by a self restoring push button switch R, which, when not actuated, makes contact at point 36, and when actuated, breaks this contact and makes contact at point 70. A source of electrical energy is conventionally represented by battery B, with the usual positive and negative busses and an additional indicator lamp bus (so designated), for the cross indicator circuit.

Before describing the operation and tracing the circuit of this traffic controlling system, the construction of the protective device included in this invention, will be considered.

Referring to Fig. 2 of the accompanying drawings, the protective device embodying the present invention, as illustrated, includes

a U-shaped permanent magnet Mg, having one end secured to a soft iron extension 1 by a bolt 2, this same bolt also serving to mount the device on a panel or similar support (not shown). A dowel pin 3 is provided to assure that the device is in a predetermined position on its support.

To the lower end of the soft iron extension 1 is fastened a core 4 terminating in a large circular pole piece 5. On the core 4 are provided coils 6 and 7, for purposes more clearly explained hereinafter.

The free end of the permanent magnet M, has secured thereto a triangular, or wedge-shaped, block 8 fastened in place by a bolt 9, and conveniently called a bearing block. It is of suitable material, such as tempered steel, to provide a durable, frictionless, knife-edged bearing for an armature 10. The armature 10 has its extreme right end bent up and then down, to form a groove fitting directly over the knife edge portion of bearing block 8, the bearing block being provided with a screw 11 passing through an oversized opening in armature 10, with its head normally spaced from the armature itself. This holds the armature in place in the event of extreme jars or the like, but does not offer any resistance to motion of the armature about its pivotal knife edge support.

Secured to the armature 10 but electrically insulated from it, are two contacts 12 and 13 (see Fig. 3), which are electrically connected to each other by a strap 14. The armature 10, pivoting about its knife edge support 8, is able to come in contact with either the pole face 5 or the extension 1, and since both the core 4 and the extension 1 are constructed of soft iron, the magnetic flux due to the permanent magnet M ordinarily passes equally well through either of the two extending members. Thus, when the armature 10 is against either of these members, it makes that path of the lesser reluctance, and consequently the armature stays in whichever position it is placed.

The soft iron extension 1 is recessed to receive a terminal and contact mounting board 15, which carries two U-shaped contact fingers 17 held in place in grooves by terminal posts 16. These contact fingers are provided with suitable contacts 17¹ at their free ends, which are engageable by contacts 12 and 13 on armature 10. An adjustment means for the tractive force on the armature in the normal or raised position, is provided by screw 18, conveniently called a residual pin, and made of some non-magnetic material, which is threaded into extension 1 and is locked in an adjusted position by a nut 19. By means of this pin, the air gap in the normal magnetic circuit can be varied, thereby directly adjusting the sensitiveness of the device, for the reason that the force necessary to drop the armature depends on the magnetic at-

traction of the armature to its normal position.

Mounted on terminal board 15, is another pair of binding posts 20 and 21, which support two curved spring contact fingers 22 and 23. Spring contact 23 is made slightly longer than spring contact 22, to thus permit a plunger 24, resting on armature 10, and slidably mounted through terminal board 15, to engage with contact 23 and lift it clear of contact 22, when said armature lifts the plunger 24 by moving to its normal position. When armature 10 is released from its normal position, plunger 24 is allowed to drop, permitting contact 23 to engage with contact 22 through suitable low resistance points at their free ends.

The operation of the switch machine and the application of unauthorized current to certain parts of the circuit will now be discussed, to thus obtain a clear understanding of the operation of the protective device just described, when used in such a circuit as shown in Fig. 1.

Assuming that the operator desires to move the track switch TS from its normal position, as shown, to its reverse position, and also assuming that its control lever is not locked by other conflicting control levers, he pulls the lever L until the contact blocks 28 and 29 engage with the reverse contacting springs 30 and 31, while further movement in the same direction is prevented because of latch bar 32. The lever L has now assumed the half reverse position which completes a circuit as follows:—beginning at the positive side of battery B, wires 33 and 34, self restoring push button switch R, contact 36, wire 37, positive bus, wire 38, coils of safety magnet S, wire 39, contact fingers 31, contact 29, wire 40, reverse control wire RW, contacts 41, movable contact 42, wires 43 and 44, motor armature M, wire 45, contacts 46, movable contact 47, wire 48, motor field winding F, common return wire C, wire 49, contacts 17, armature 10, wires 50 and 51, negative bus, wire 52, back to negative battery B.

The completion of this circuit causes the switch machine motor to operate in such a direction as to move the switch points to the reverse position, and at the completion of this stroke, the pole changer contacts 42 and 47 are moved into a position making contact between the two fingers 53 as well as between the two fingers 54. This movement prepares the motor for returning the switch to its normal position upon return of the lever, as well as utilizes the dynamic energy of the revolving armature to indicate that the switch machine has performed its function. The generation of this dynamic current has a desirable snubbing action on the motor. The direction in which this dynamic current flows in the armature will depend on

the direction of rotation of the armature, but due to the fact that the armature is pole-changed by movable contacts 42 and 47 its relative polarity with respect to the field is independent of the direction of rotation, thus permitting the dynamic current to flow in a definite direction through the indication circuit, under normal conditions, which is as follows:—beginning at the armature of the motor M, wire 44, contact fingers 54, movable contact 47, wires 55 and 48, motor field winding F, common wire C, wire 65, operating coil 6 of protective device P¹, wire 56, indication magnet coils IM, wire 57, contact fingers 30 of control lever L, contact 28, wire 58, normal control wire NW, contact fingers 53 of pole changer, movable contact 42, wire 59, wire 45 back to armature of the motor M.

By looking at Fig. 2 it will be noticed that armature 10, having been placed in the normal position will remain there due to the fact that the major part of the flux is passing through extension 1, and through armature 10 to the permanent magnet M_g, thereby attracting armature 10 to its raised position against extension 1. The operating coil 6 is so arranged that current flowing in the normal direction through the indication circuit, just traced, produces a flux which aids the passage of flux from the permanent magnet through the extension 1 and in this way produces a stronger attraction between the armature 10 and extension 1. This current flowing in the indication circuit has the purpose of causing the armature of indication magnet IM to be attracted, thus effecting operation of the latch 60 which operates latch bar 32, thereby unlocking the lever L to permit the operator to complete the stroke of this lever to a full reverse position, which stroke, when completed, unlocks certain other conflicting or associated levers.

When the operator desires to return the switch to its normal position he pushes the control lever L back to its normal position, providing it is not locked by conflicting levers, and a circuit is completed which is very similar to the reverse operating circuit already traced. The indicating current will be received the same as in the reverse operation and in the same direction, as heretofore described, and its effect on the indication magnet IM, and the protective device

will be identical.

However, in the event of an abnormal condition on the control wires or connections such as a cross, a ground or short circuit of such a nature as to allow current to flow between control wires RW and NW, the current might tend to flow in the opposite direction and operate the indication magnet IM, if it were not for the action of the protective device which is as follows:—the current from battery B will flow through wires

33 and 34, self restoring push button R, contact 36, wire 37, positive bus, wire 38, safety magnet coils S, wire 39, wire 61, contact fingers 62, contact 29, normal control wire NW, through the unauthorized connection to reverse control wire RW, contact fingers 63, contact 28, wires 64 and 57, indication magnet coils IM, wire 56, operating coil 6 of safety device P¹, wires 65 and 49, contacts 17, armature 10, wire 50, wire 51, negative bus, wire 52, back to battery B.

It will be noted that this is in a direction opposite to the normal flow of current through the operating coil of the protective device, and the flux set up in core 4 (see Fig. 2) by this current is in such a direction as to aid the passage of flux from the permanent magnet M_g through the core 4, depriving the extension 1 of the major part of its flux, and decreasing the retaining force on the armature 10 to such an extent that it is both attracted magnetically and by gravity to pole face 5. This breaks the circuit between the armature contact fingers 12 and 13, and the stationary contacts 17¹, which prevents the further operation of the switch machine until the abnormal condition has been remedied. The armature dropping to its lower position will release plunger 24, allowing contact 23 to close on contact 22, closing a circuit to cross indicating lamp I as follows:—beginning at battery B, wires 33 and 66, indicating lamp I, wire 67, indicator lamp bus, wire 68, contacts 22 and 23, wires 69 and 51, negative bus, wire 52 and back to battery B.

The second protective device P², with its switch machine SM² having connections NW², RW² and C² together with its protective relay P², have been included to show the circuit arrangement for a plurality of protective devices, corresponding to the number of devices to be protected.

When the operating circuit is again to be restored, the operator actuates push button R, which opens the circuit of the positive battery to positive bus, thereby preventing the operation of any device, while this push button is in said actuated position.

Also, the operation of push button R applies energy to restoring coil 7 of the protective device, and this coil is connected in series with the restoring coils of all of the protective devices in the system through the following circuit:—beginning at battery B, wires 33 and 34, push button switch R, contact 70, wire 71, restoring coil 7, wire 72 to a plurality of restoring coils on the total number of protective devices, returning to negative bus, as indicated, by wire 73, and then by wire 52 to battery B.

Referring again to Fig. 2, the restoring coil 7 is so arranged that the flux, produced by current flowing in this circuit, opposes the flux in the core 4 produced by the permanent

- magnet, and strengthens the flux in extension, controlling device; a source of current; an actuator to the extent of causing sufficient force to act on the armature 10 to raise it from pole 5 to its normal position against extension 15; If the control circuit is now in its normal condition, the armature will remain raised as the low reluctance path is through the armature and extension, as previously explained, and the push button, being self restoring, again connects the positive side of the battery to the positive bus as soon as the operator releases it. But the circuit is never held closed, as the protective device is in a condition to interrupt the circuit the instant it is closed by releasing push button R. The protective device also inter-rupts the cross indicating lamp circuit through contacts 22 and 23, thereby indicating to the operator that the circuit is again in condition to operate normally.
- A reverse current protective device has thus been provided, which is adapted to open a circuit if the current in a given circuit flows in the reverse direction to that which it normally flows, as well as to close a circuit to indicate that an abnormal condition exists. Provision is also made for reclosing the circuit interrupted by the device, without forcibly holding the circuit closed while doing so.
- Having thus shown and described one specific embodiment of the present invention, and having shown it applied to a single circuit arrangement, it is desired to be understood that this has been done for the purpose of showing how the invention may be applied, rather than illustrating its scope or the exact construction preferably employed in practice; and that the specific construction shown is susceptible of considerable modifications to adapt the invention to the particular interlocking system and particular traffic controlling system to which the invention is applied, all without departing from the scope of the invention or the idea of means underlying the same.
- Having thus described my invention, what I claim is:
1. An interlocking system comprising, in combination, an electrically operated traffic controlling device; a source of current; an operating circuit for said device including contacts controlled by a lever of the interlocking system, control wires and common return wire; a dynamic indicating circuit for said traffic controlling device including one of said control wires, said common return wire, an indicating means, and a cross protection device with an armature included in its magnetic circuit; said source of current being disconnected by the operation of said armature to its abnormal position; and an electro-responsive, manually controllable means for restoring said armature to its normal position.
  2. In an electric interlocking system; in combination, an electrically operated traffic
  3. In an electric interlocking system; in combination, an electrically operated switch machine; a source of current; an operating circuit for said switch machine; a dynamic indicating circuit for said switch machine including a cross protection device, constructed to distinctly respond to current flowing in an abnormal direction in said indicating circuit to assume an abnormal position; electro-responsive restoring means for said cross protection device restoring it to its normal condition; said means disconnecting said source of current from the operating circuits while applying said source of current to said restoring means.
  4. An interlocking system comprising, an electrically operated traffic controlling device including a motor; a source of current; an operating circuit for said device; a dynamic indicating circuit for said device including a cross protection device having an armature included in its magnetic circuit; means for interrupting said operating circuit by the operation of said armature; said cross protection device including contacts held open by said armature in its normal position and allowed to complete a circuit by the operation of said armature from its normal position and means in the circuit completed by said contacts to indicate the condition of the cross protection device.
  5. In an interlocking system, in combination, a plurality of switch machines, means for energizing said switch machines, levers for controlling said switch machines, a plurality of cross protection relays for respectively protecting said switch machines, an electro-responsive restoring means for each of said cross protection relays, and a single manually operable reset control for energizing all of said reset means.
  6. In an interlocking system, in combination, a plurality of switch machines, levers for controlling said switch machines, a plurality of cross protection devices for respectively protecting said switch machines, an electro-responsive restoring means for each of said cross protection devices, and a single manually operable reset control for energizing all of said restoring means, said reset control, when energizing said restoring

means, operating to deenergize said switch machines.

7. In an interlocking system, in combination, a plurality of traffic controlling devices, levers for controlling said traffic controlling devices, a plurality of cross protection devices associated with said traffic controlling devices, an electro-responsive restoring means for each of said cross protection devices, and a single manually operable reset control for energizing all of said restoring means, said reset control, when energizing said restoring means, operating to deenergize said switch machines, and a single indicating means controlled by each of said cross protection devices.

8. In an interlocking system for railroads, a switch machine, operating circuits for the switch machine for operating it to normal and reverse positions respectively, a control lever governing said operating circuits, a protective device having contact means included in said operating circuits, means opening said contacts when abnormal current flows in said operating circuits, and electro-responsive means for closing said contacts.

9. In an interlocking system for railroads, a switch machine having operating circuits, a control lever governing said operating circuits, a protective device having contacts and two windings for opening and closing said contacts respectively, means including said contacts in said operating circuits, means energizing one of said two windings for opening said operating circuits when abnormal current flows therein, a manually operable contact means for energizing the other of said two windings for closing said contacts, said manually operable contact means simultaneously opening said operating circuits, and means returning said manually operable contact means to normal to close said operating circuits if said contacts of said protective device are closed.

45 10. In an interlocking system for railroads, a switch machine having operating circuits, a control lever governing said operating circuits, a protective device effective for opening said operating circuits when abnormal current flows therein, said device having electro-responsive means for restoring said protective device to normal for closing said operating circuits, and contact means manually operable for actuating said electro-responsive 55 means of said protective device and for simultaneously opening said operating circuits only until said electro-responsive means ceases to be actuated.

60 11. In an interlocking system for railroads, a switch machine having operating circuits of the dynamic indication type, a polarized cross protection relay included in said operating circuits, said relay being responsive only to abnormal current due to crosses, an electro- 65 responsive restoring means for said polarized

cross protection relay, a self-restoring contact means for closing a circuit for said electro-responsive restoring means and opening said operating circuits when actuated, said self-restoring contact means closing said operating circuits when not actuated.

70 12. In an interlocking system for railroads, a switch machine having operating circuits of the dynamic indication type, a cross protection relay comprising a permanent magnet having two extensions of soft iron fastened to one of its ends, two coils on one of said extensions, an armature pivotally supported by the other end of said permanent magnet and operable to either of two positions into contact with one or the other of said two extensions, means including one of said coils in said operating circuits in a manner that current flow due to normal operation of said switch machine actuates said armature to one of its two positions and abnormal current actuates said armature to the other of its said two positions, contacts operated by said armature and adapted to open said operating circuits when said armature is actuated by abnormal current, and means for energizing said other coil so as to actuate said armature to its said one position subsequent to actuation of said armature to its other position.

75 13. In an interlocking system for railroads, a switch machine, operating circuits for the switch machine for operating it to normal and reverse positions respectively, a control lever governing said operating circuits, a protective device having contact means included in said operating circuits, means opening said contacts when abnormal current flows in said operating circuits, and manually controllable electro-responsive means for closing said contacts.

80 In testimony whereof I affix my signature.
JOHN C. LINDNER.
